(57) CLAIM

The ornamental design for a football shaped absorbent urine pad, as shown and described.

DESCRIPTION

FIG. 1 is an isometric view of a football shaped absorbent urine pad showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and,

FIG. 8 is my design in an operational setting adhered to boxer shorts.

The broken line showing of boxer shorts in FIG. 8 depicts environmental subject matter which forms no part of the claimed design. All other broken lines depict portions of the football shaped absorbent urine pad that form no part of the claimed design.
